(57) **CLAIM**

I claim the ornamental design for a hand grip, as shown and described.

DESCRIPTION

FIG. 1 is a front perspective view of a hand grip in accordance with my new design;

FIG. 2 is a top plan view of the hand grip of FIG. 1;

FIG. 3 is a left side elevational view of the hand grip of FIG. 1, the right side elevational view being a mirror image thereof;

FIG. 4 is an enlarged front elevational view of the hand grip of FIG. 1;

FIG. 5 is an enlarged rear elevational view of the hand grip of FIG. 1; and,

FIG. 6 is a bottom plan view of the hand grip of FIG. 1. The broken lines shown in the figures represent portions of the hand grip that form no part of the claimed design.
